UNITED STATES PATENT OFFICE.

WILLARD R. WALKER, OF SYRACUSE, NEW YORK.

SWINGING SHELF.

1,114,948.

Specification of Letters Patent. Patented Oct. 27, 1914.

Application filed December 10, 1912. Serial No. 735,908.

To all whom it may concern:

Be it known that I, WILLARD R. WALKER, of Syracuse, in the county of Onondaga, in the State of New York, have invented new and useful Improvements in Swinging Shelves, of which the following, taken in connection with the accompanying drawings, is a full, clear, and exact description.

This invention relates to certain improvements in swinging shelves adapted to be applied more particularly to hospital beds, chairs and other available supports for receiving and supporting food trays, books, writing material, and other articles for the convenient use of patients or other persons reclining or sitting upon such beds, cots, chairs or similar pieces of furniture.

The primary object is to provide a simple and comparatively inexpensive device of the character described which may be easily and quickly applied to a bed post, chair post or other available support in proximity to a bed, cot or chair and adjusted vertically or horizontally or to different angles as may be required for the convenience of the occupant of the bed, cot or chair for supporting any of the articles which may be necessary or desirable for the comfort of such occupant.

Another object is to enable the various parts of the device to be quickly assembled or folded into compact space for storage or transportation or similarly folded into a relatively small space and shifted to one side out of the way when not in use without detaching it from its support.

A further object is to make the shelf proper in sections hinged to each other so as to fold one upon the other and to secure the supporting bracket directly to the front section which is subjected to the greatest strain or load.

Other objects and uses will be brought out in the following description.

In the drawings—Figure 1 is a perspective view of a swinging shelf embodying the various features of my invention and shown as attached to a bed or chair post. Fig. 2 is a transverse sectional view through the shelf proper and adjacent portion of its supporting bracket taken on line 2—2, Fig. 1. Fig. 3 is a lengthwise sectional view through the same shelf and adjacent portion of its supporting bracket taken on line 3—3, Fig. 4 is a horizontal sectional view through the clamp and post to which it is

secured taken on line 4—4, Fig. 1. Fig. 5 is a longitudinal vertical sectional view, partly in elevation, of portions of two of the bracket sections and clamp and adjacent portion of the supporting post to which the clamp is secured.

As shown in the drawings, this device comprises a sectional bracket —1— having one end adapted to be secured to a bed or chair post —a— or equivalent support and a sectional shelf or tray —2— adjustably secured to the opposite end of the bracket in the manner presently described.

The bracket —1— preferably consists of a sectional clamp —3— and a plurality of, in this instance three, tubular arms or sections —4—, —5— and —6— pivotally connected respectively to the clamp —3— and to each other for horizontal swinging adjustment, said bracket being also provided with a vertically adjustable shelf-supporting head —7— which is pivotally mounted upon one end of the section —6— as shown more clearly in Fig. 2.

The clamp —3—, as shown in Fig. 4, comprises opposite relatively adjustable sections —8— and —9— having centrally registering concave seats —10— adapted to engage opposite sides of the post —a—, the clamping section —8— being provided at its opposite ends with clamping bolts —11— which are passed through apertures in the corresponding ends of the section —9— and provided with thumb nuts —12— for drawing the clamping sections —8— and —9— tightly against opposite sides of the post —a— and, at the same time permitting the bracket and shelf to be adjusted vertically or rotatably along and around said post as may be required to suit the convenience of the user.

The clamping section —8— is provided with a laterally projecting cylindrical offset —13— having a vertical cylindrical socket or bore —14— for receiving one arm of an elbow coupling —15— on the adjacent end of the tubular bracket section —4—. The arm of the coupling —15—, which enters the socket —14— is also cylindrical and fitted with an easy turning fit in said socket and is provided with an annular shoulder —16— resting upon the upper end of the tubular offset —13— for limiting the downward movement of the coupling and at the same time permitting it to be readily withdrawn upwardly from its socket. The other arm of the hollow coupling —15— is rigidly se-

cured by screw threads or otherwise to the adjacent end of the bracket section —4— so as to form practically a unitary part thereof.

The central portion of the clamping section —8— is provided with a pendant extension —17— forming a continued seat —10— adjacent the offset —13— so as to better resist downward and lateral strains upon this portion of the clamp and its support incidental to any load which may be placed on the shelf.

The outer end of the bracket section —4— is provided with a coupling section —18— screwed or otherwise secured thereto and having a vertical cylindrical socket or bore —19— for the reception of the cylindrical arm of another elbow section —15'— which is similar to that previously described and is provided with an annular shoulder —16— resting upon the upper face of the coupling section —18— so as to limit the downward movement of the bracket section —5— and, at the same time, permit said bracket section to be removed upwardly from its socket —19— when desired. The lower arm of the elbow section —15'— is also fitted with an easy turning fit in the coupling section —18— so as to permit the bracket arms —4— and —5— to be adjusted rotatably relatively to each other. In like manner, the outer end of the bracket section —5— is provided with a coupling section —18'— screwed or otherwise secured thereto and is substantially the same as the coupling —18— and, therefore, provided with a vertical socket or cylindrical bore —19'— for receiving the upright cylindrical arm of the tubular elbow section —6— which is also provided with an annular shoulder —20— resting upon the upper face of the coupling section —18'— for limiting the downward movement of the elbow section —6— and at the same time permitting such elbow section to be withdrawn upwardly when desired, it being understood that the lower end of the elbow section —6— is cylindrical and fitted with an easy turning fit within the socket —19'—.

The outer end of the elbow section —6— is furcated and provided with opposite enlarged concavo-convex bearings —21— spaced apart a sufficient distance to receive between them a pendant arm —22— on the underside of the head —7—. The concave sides of the arms —21— face each other and form opposed annular bearings —23— for engaging the opposite sides of the pendant projection —22— to which said arms are clamped by means of a screw —24— passing through the registering apertures in the arms —21— and pendant projection —22—, the central aperture in one of the arms —21— being threaded to engage the adjacent end of the screw while the opposite end of the screw is enlarged to engage the

outer face of the opposite arm —21— as shown more clearly in Fig. 3, thus permitting the head —22— to rock vertically upon the pivotal bolt or screw —24—. The head —22— is provided with a substantially flat upper face to which the shelf —2— is secured by suitable fastening means as screws —25— through the medium of an intervening cleat or plate —26—. This shelf is preferably composed of front and rear sections —27— and —28—, arranged edge to edge and hinged to each other at their ends by upstanding hinges —29— which form guards to hold articles on the shelf against lateral displacement. The front edge of the front section is also provided with an upstanding flange —30— to hold such articles against sliding from the shelf when the latter is tilted as shown in Fig. 2. The front section —27—, which receives the greatest load and strains, is rigidly secured to the head —7— in such manner as to allow a small portion of the rear edge of the plate —26— to project rearwardly beyond the meeting edges of the shelf sections —27— and —28— so as to afford ample support for the rear shelf section without liability of overstraining the hinges and, at the same time, permitting said rear section to fold upwardly and forwardly over and upon the front section as shown by dotted lines in Fig. 2.

It will be seen from the foregoing description that the bracket for supporting the shelf comprises bars or arms —4— and —5— having elbows at one end and sockets at their opposite ends, the elbow of one of said sections being fitted with an easy turning fit in the socket in the adjacent end of the other section while the other elbow of one of the first named sections is fitted with an easy turning fit in the socket of the clamp and the elbow section —6— is similarly fitted in the socket of the other of the first named sections, thereby allowing a wide range of horizontal adjustment of the shelf while the shelf itself may be tilted or adjusted vertically to different angles and may be used as a table, writing desk, book support and various other apparatus.

What I claim is:

1. A swinging shelf comprising an articulated bracket having its sections hinged to each other to swing horizontally, one of the end sections having means for clamping it to a suitable support, a shelf-supporting head hinged to the other end section to swing vertically, and a folding shelf composed of sections hinged together edge to edge to swing vertically about an axis parallel with that of the vertically swinging head, said head being rigidly secured to one of the shelf sections and extended under the other shelf section to form a rest therefor when unfolded.

2. A swinging shelf comprising a horizontally swinging bracket, a shelf supporting head pivoted to the bracket to swing vertically, a folding shelf composed of sections hinged to each other edge to edge to permit one of the sections to be folded over and upon the other section on an axis parallel with that of the head, the other section being secured to the head, said head ex-

tending to opposite sides of the meeting edges of the shelf sections to form a rest for the folding section.

In witness whereof I have hereunto set my hand this 5th day of December, 1912.

WILLARD R. WALKER.
